UNITED STATES PATENT OFFICE.

SOLON BRYANT, OF WORCESTER, MASSACHUSETTS.

DESIGN FOR A CORSET.

SPECIFICATION forming part of Design No. 21,544, dated May 17, 1892.

Application filed November 30, 1891. Serial No. 413,601. Term of patent 3½ years.

To all whom it may concern:

Be it known that I, SOLON BRYANT, of Worcester, in the county of Worcester and State of Massachusetts, have invented a new 5 Design for Corsets; and I do hereby declare the following, when taken in connection with accompanying drawings and the letters of reference marked thereon, to be a full, clear, and exact description of the same, and which said 10 drawing constitutes part of this specification, and represents a perspective side view.

This invention relates to a design for the ornamentation of a corset, with special reference to the side portions thereof; and it consists in 15 the ornamentation of the corset as shown in the accompanying illustration. On the side or hip portion A of the corset is the representation of a series of vertical ribs starting from the lower edge of the corset and running 20 up to about the waist-line, there divided, the two parts diverging, one portion represented

as running toward the front and the other portion represented as running toward the rear to the upper edge of the side. At the lower edge of the corset and each side of the said 25 central ribs is the representation of gores D E, presenting the appearance of a series of transverse ribs contracting in length until they die out at about the waist-line, as at b c. B represents the rear portion, and C the 30 front portion, of the corset.

I claim—

The design for a corset, as herein shown and described.

In testimony whereof I have signed this 35 specification in the presence of two subscribing witnesses.

SOLON BRYANT.
